(57) **CLAIM**

The ornamental design for a control panel for elevator, as shown and described.

DESCRIPTION

FIG. 1 is a front, top and right side perspective view of a control panel for elevator, showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a right side elevational view thereof;

FIG. 8 is a cross-sectional view thereof; taken along the line 8—8 of FIG. 2; and,

FIG. 9 is a reference view with the light-transmitting portions drawn by oblique lines.

The broken lines depict unclaimed environmental subject matter.
